UNITED STATES PATENT OFFICE.

JOHN W. BAMFORD, OF PASCOAG, RHODE ISLAND.

CAP-SPINDLE.

SPECIFICATION forming part of Letters Patent No. 619,064, dated February 7, 1899.

Application filed February 10, 1898. Serial No. 669,754. (No model.)

To all whom it may concern:

Be it known that I, JOHN W. BAMFORD, of Pascoag, in the county of Providence and State of Rhode Island, have invented a new and useful Improvement in Cap-Spindles; and I hereby declare that the following is a full, clear, and exact description of the same, reference being had to the accompanying drawings, forming part of this specification.

10 This invention has reference to an improved lubricating device for spindles of cap-spinning machines; and it consists in the peculiar and novel construction of an oiling-cup whereby oil is used over and over and filtered before each use or reuse, as will be more fully set forth hereinafter.

15 In spindles for cap-spinning machines the whirl and bobbin-support are made to travel up and down on the dead-spindle. A portion 20 of the spindle covered with lubricating-oil is exposed to the atmosphere of the spinning-room, which is more or less, but always considerably, loaded with fine dust and floating fiber, which adhere to the oil-covered part of 25 the spindle and mix with the lubricating-oil, into which they are carried by the reciprocation of the bolster-rail and the oiling device.

20 The object of this invention is to provide for the taking up of the surplus oil from the 30 spindle and passing the oil through a straining material before it is again brought into contact with the spindle.

25 Figure 1 is a vertical sectional view of a cap-spindle provided with my improved oiling device. Fig. 2 is a top view of the oiling device. Fig. 3 is a bottom view of the lower oil cup or tray and holding device. Fig. 4 is a sectional view through the center of the two oil-cups and the holding device, showing the 35 same secured together by a thimble. Fig. 5 is a top view of the cover, and Fig. 6 is a top view of the lower oil cup or tray.

Similar letters of reference indicate corresponding parts in all the figures.

40 I have elected to illustrate my improved oiling device in connection with the rail as usually found in cap-spinning machines.

45 In the drawings, *a* indicates the stationary spindle of a cap-spinning machine; *b*, the reciprocating rail by which the bobbin and its support are moved up and down; *c*, the band-pulley or whirl, and *d* the bobbin-tube. The

55 whirl *c* is provided with the recess *e*, formed by the depending flange *e'*, and the bearing-block *n*. This bearing-block is forced over the downward extension of the tube *d*, so as to be driven by the whirl and may be formed of any suitable material. The tray *g* is provided with a central hole and the oil-holes *h*. The cup *i* has a central hole and the oil-holes *l* and annular sides, which extend upward into the recess *e* of the whirl.

60 The various parts of the oiling device are secured together in the following order: The two pieces of felt *o o* are placed in the tray *g* over the holes *h h*. The cup *i* is then placed with that portion of the bottom not having the holes in it so as to rest on the felt pieces *o o*. The thimble *k* is now passed through the central hole in the cup *i* and through the 65 central hole in the tray *g*. The holding-clamp *r* is then placed on the lower end of the thimble *k* with the two holes *s s* under the holes *h h*, and then the lower end of the thimble *k* is spun over to hold all the parts in 70 position. The upper flange of the thimble *k* forms an annular raised surface, on which the bearing-block *n* of the whirl is supported and revolved. *m* is a felt washer. This washer 75 may be placed on the flat top of the rail *b*, as shown in Fig. 1, or a recess may be made in the rail to receive the felt washer. The holding-clamp *r* extends outward and is bent around the rail, as shown in Fig. 1, to hold 80 the oiling device against rotation.

85 I will now more fully describe the operation of the oiling device. The lubricating-oil is placed into the tray *g* through the openings *q q* in the cover *p*, which covers the tray and prevents flying pieces of lint or fiber from lodging therein. The oil passes through the felt pieces *o o*, through holes *h h* in the tray *g* and through the holes *s s* in the holding-clamp *r*, into the felt washer *m*, and in passing through the felt pieces *o o* and the felt washer *m* deposits any impurities held in suspension in the oil. The felt of the washer *m* being in contact with the spindle *a* supplies oil to the spindle. As the whirl *c* and tube *d* are moved up and down any surplus oil on the spindle between the upper surface of the thimble *k* and the lower end of the bearing-block *n* is thrown outward by the rapidly-revolving edge *f* of the bearing-block 90 95 100

into the cup *i* and passes through the holes *l l* into the tray *g*, from which the oil filters through the pieces of felt *o o* and passes through the holes *h h s s* into the felt washer *m*. The impurities in the oil are retained by the fibrous material of the felt pieces and felt washer, and the filtered oil is delivered to the spindle.

Economy in the use of oil, cleanliness by preventing the throwing off of the oil, and perfect lubrication are secured by the use of this device, which can be adapted to any form of cap-spinning machine.

Having thus described my invention, I claim as new and desire to secure by Letters Patent—

1. In a lubricating device for cap-spinning machines, the cup *i* provided with holes, the tray *g* provided with holes, the felt pieces *o o*, placed under the solid portion of the cup *i* and over the holes *h h*, in the tray, and the

thimble *k* for securing the cup and tray together and compressing the felt pieces *o o*, between the same, substantially as herein shown and described.

2. In a cap-spinning machine, the combination with the spindle *a*, the tube *d*, the whirl *c* provided with the flange *e* and the bearing-block *n*, and the rail *b*, of the cup *i* having holes *l l*, in the bottom, the felt pieces *o o*, the tray *g* provided with the holes *h h*, the holding-clip *r*, the thimble *k* for securing the cup, the tray, and the clip together and the upper flange of which forms the bearing for the whirl, and the felt washer *m*, all substantially as herein shown and described.

In witness whereof I have hereunto set my hand.

JOHN W. BAMFORD.
